UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,267,621.

Specification of Letters Patent. Patented May 28, 1918.

Application filed July 20, 1915. Serial No. 40,896.

To all whom it may concern:

Be it known that I, JOSEPH BERGER, Jr., a citizen of the United States, residing at Utica, in the county of Oneida, State of New York, have invented certain new and useful Improvements in Presser-Feet for Sewing-Machines, of which the following is a description, reference being had to the accompanying drawing and to the figures 10 of reference marked thereon.

The invention relates to new and useful improvements in a presser foot for sewing machines, and more particularly to a presser foot which coöperates with a feeding and trimming and a stitching mechanism for joining or covering the edges of fabric sections.

An object of the invention is to construct a presser foot of the above character having means for supporting the stationary member of a trimming mechanism and also a guiding channel for directing the upturned edges of fabric sections to said trimming mechanism, with needle openings 20 adapted to receive needles arranged in pairs, one in rear of the other, wherein the needles of the respective pairs are staggered relative to each other.

A still further object of the invention 30 is to provide a device of the above character with a strip guide for directing the trimmed-off strip, which strip guide is made in sections, one of which is movable so as to facilitate the threading of the 35 needles or the changing of the needles.

These and other objects will in part be obvious, and will in part be hereinafter more fully disclosed.

In the drawings which show by way of 40 illustration one embodiment of the invention,—

Figure 1 is a view in side elevation, showing a presser foot having my improvements and also the end of the work support, the 45 needle bar and needles, and a portion of the supporting head of the machine, the foot being elevated;

Fig. 2 is a front view of my improved presser foot;

Fig. 3 is a plan view of the same showing also the movable trimming member; and

Fig. 4 is a perspective view of the presser foot with parts thereof detached and with

the strip deflector turned to one side where- 55 by access may be had to the needles.

My improved presser foot consists of the main supporting shank 1, which is carried by a presser bar extending into the socket 2. This presser foot is formed with a main 60 presser foot section 3 which is rigid on the shank 1 and a yielding or auxiliary presser foot section 4 which is slidingly supported by said shank. The auxiliary section 4 is formed with an auxiliary shank 65 5. This shank fits between the lugs 6 and 7 on the main shank 1 and a cover plate 8 secured by screws 9—9 to the lug 7 which holds the auxiliary shank on the main shank but permits the same to slide vertically. 70

A spring 10 secured by a screw 11 to the main shank 1 of the presser foot, extends upwardly and forwardly over the auxiliary shank as at 12. This spring bears on an upwardly projecting lug 13 formed integral with the shank 5. Said spring normally forces the section 4 downwardly so that the lower face thereof projects below the lower face of the main section 3.

The auxiliary shank 5 is formed with an 80 elongated vertical slot 14 and a screw 15 passes through the cover plate 8, the elongated slot 14 and is threaded into the opening 16 in the main shank. This screw limits the downward movement and the lug 6 85 limits the upward movement of the auxiliary portion 4 of the presser foot.

The main section 3 of the presser foot is provided with two needle openings 17 and 18; and the foot is provided with two 90 stitch tongues 19 and 19^a which respectively extend into said openings. The needle opening 18 is in rear of the needle opening 17, and as shown in Fig. 3 said openings are offset or staggered relative to 95 each other in the direction of the line of feed. The needles 20 and 21 enter the needle opening 17 on opposite sides of the stitch tongue 19, while the needles 22 and 23 enter the needle opening 18 on the opposite side of the stitch tongue 19^a in said opening. A suitable cross stitch-forming mechanism coöperates with each pair of needles above and below the material and two independent seams are, therefore, made 100 by the respective pairs of needles, which seams overlap each other as above noted.

The main section of the foot 3 has a for-

wardly and upwardly projecting portion 24. This forwardly projecting portion is set back from the inner edge of the main section to form a space 25. The auxiliary section 4 is also provided with a forwardly and upwardly projecting portion 26, which overlaps slightly the main section 3, but the inner edge 27 of this portion 26 is spaced from the inner edge 28 of the projecting portion 24, thus forming a fabric-guiding channel 29.

A stationary trimmer blade 30 is seated in a recess in the upper face of the presser foot and is held therein by a clamping plate 31 and a clamping screw 32. The cutting edge of the stationary trimming member is substantially in line with the inner edge 28 of the projecting portion 24. This inner edge 28 is in a line passing between the stitch tongue in the needle openings 17 and 18. Coöperating with the stationary trimming member 30 is a movable trimming member 33. This stationary trimming member is carried by the main fixed section of the presser foot, and, therefore, the edges of the fabric will be trimmed at a uniform distance above the lower face of the main section of the foot.

A strip deflector 34 is secured by screws 35 to an arm 36 which is pivoted at 37 to the projecting portion on the main shank 1. A spring 38 is secured to the arm 36 by screws 39. This spring bears against the flat face of the projection carrying the pivot 37 and will hold the strip deflector in the position shown in Fig. 3 of the drawings. When said strip deflector is turned to the position shown in Fig. 4, then said spring bears against the rear face of said projection and holds the deflector in this position shown in said Fig. 4.

The strip deflector 34 is formed in two sections. The section 39^a is rigidly secured to the main section of the presser foot and extends across the guiding channel 29. The outer end of this fixed section of the strip deflector bears against a vertical lug 40 secured to the auxiliary section 4 of the presser foot by a screw 41. This lug serves to prevent the free end of the strip deflector from being forced rearwardly by the fabric. Said fixed section 39^a is cut away on its under face to form a clearance for the movable trimming blade 33. As the free end 55 of the strip deflector merely rests against the lug 40, the auxiliary section of the presser foot has free vertical movements. The movable section of the strip deflector is shaped to conform in a general way with the fixed section and the lower edge of said movable section will turn freely above the raised portions of the presser foot which clamp the stationary trimming member.

The presser foot coöperates with the feed mechanism 42 operating at the free end

of the work supporting arm 43. The main shank of the presser foot has a rearwardly projecting arm 44 which is forked at 45 so as to slidingly engage the auxiliary presser bar 46. This permits the presser foot to be raised and lowered but holds the same from turning on the presser bar or the presser bar from turning, due to the lateral force of the trimming operation.

It is obvious that minor changes in the details of construction and arrangement of parts may be made without departing from the spirit of the invention as set forth in the appended claims.

Having thus described my invention, what I claim as new and desire to secure by Letters Patent, is:—

1. A presser foot for sewing machines including in combination, a supporting shank, a main foot portion rigidly connected to said shank and having means for supporting the stationary member of a trimming mechanism, said presser foot having a guiding channel for directing the edges to be trimmed to the trimming mechanism, said foot portion having needle openings therein, one of said openings being in rear of the other and offset relative thereto in the direction of the line of feed.

2. A presser foot for sewing machines including in combination, a supporting shank, a main foot portion rigidly connected to said shank and having means for supporting the stationary member of a trimming mechanism, said presser foot having a guiding channel for directing the edges to be trimmed to the trimming mechanism, and a projecting arm carried by said main shank and adapted to have sliding engagement with a bar supported by the head of the machine for resisting the lateral force of the movable trimming member.

3. A presser foot for sewing machines including in combination, a supporting shank, a main foot portion rigidly connected to said shank and having means for supporting the stationary member of a trimming mechanism, said foot portion having a guiding channel for directing the edges to be trimmed to the trimming mechanism, a strip deflector carried by the presser foot and extending across said guiding channel for deflecting the trimmed off strip away from the needles, said strip deflector being formed in sections, one of which is fixed to the presser foot and the other of which is movably supported thereby.

4. A presser foot for sewing machines including in combination, a supporting shank, a main foot portion rigidly connected to said shank and having means for supporting the stationary member of a trimming mechanism, said presser foot having a guiding channel for directing the edges to be trimmed to the trimming mechanism,

- a strip deflector carried by the presser foot and extending across said guiding channel for deflecting the trimmed off strip away from the needles, means for pivotally supporting said strip deflector, whereby the same may be turned away from the needles to give access thereto for threading, and a spring for holding the strip deflector in either operative or inoperative position.
- 5 10 5. A presser foot for sewing machines including in combination, a supporting shank, a main foot portion rigidly connected to said shank and having means for supporting the stationary member of a trimming mechanism, said foot portion having a guiding channel for directing the edges to be trimmed to the trimming mechanism,

a strip deflector carried by the presser foot and extending across said guiding channel for deflecting the trimmed off strip away from the needles, said strip deflector being formed in sections, one of which is fixed to the presser foot and the other of which is movably supported thereby, said movable section being so disposed as to swing above the clamp for the stationary trimming member, and a spring for holding said movable section in operative position.

In testimony whereof, I affix my signature in the presence of two witnesses.

JOSEPH BERGER, JR.
